(57) **CLAIM**

The ornamental design for a hitch, as shown and described.

DESCRIPTION

FIG. 1 is a top rear perspective view of a hitch according to the present invention.

FIG. 2 is a bottom front perspective view of the hitch of FIG. 1.

FIG. 3 is a first side view of the hitch of FIG. 1.

FIG. 4 is a second, opposite side view of the hitch of FIG. 1.

FIG. 5 is a front view of the hitch of FIG. 1.

FIG. 6 is a rear view of the hitch of FIG. 1.

FIG. 7 is a top view of the hitch of FIG. 1; and,

FIG. 8 is a bottom view of the hitch of FIG. 1.

Any broken lines shown are directed to portions of the article which are not claimed, or to environmental structure which forms no part of the claimed design.

1 Claim, 8 Drawing Sheets

FIG. 2

FIG. 3
